UNITED STATES PATENT OFFICE.

MAURITZ C. INDAHL, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

TYPOGRAPHIC MACHINE.

1,378,413.

Specification of Letters Patent. Patented May 17, 1921.

Application filed September 12, 1919. Serial No. 323,284.

To all whom it may concern:

Be it known that I, MAURITZ C. INDAHL, a citizen of the United States, residing at Philadelphia, county of Philadelphia, State 5 of Pennsylvania, have invented certain new and useful Improvements in Typographic Machines; and I do hereby declare the following to be a full, clear, and exact description of the same, reference being had 10 to the accompanying drawings, forming a part of this specification, and to the characters of reference marked thereon.

This invention relates to type-casting and 15 composing machines of that class wherein type metal elements are cast and ejected into a galley under the control of a keyboard. An exemplification of such class of machines may be found in the well known casting and composing machines made by 20 the Lanston Monotype Machine Company in which the keyboard element is in the form of a separate machine for preparing a perforated paper strip or controller, which latter when applied to the casting 25 element controls the casting and delivery of the type bodies. The present invention has among its objects to provide a novel mechanism for selectively controlling definite functions of a casting machine of the class 30 referred to; to provide mechanism, responsive to keyboard control, for adjusting the mold of such a machine for the production of type sizes varying in pointwise direction; to provide an interpreting device 35 whereby an impulse, due to keyboard action, such as the pneumatic impulse controlled by the signals of a perforated paper controller, may be selectively utilized to govern direction of movement of as well as 40 location of an adjustable element of a casting machine of the class referred to; to provide a mechanism for moving an adjustable element of such a machine from its position at any time directly to the next 45 position as recorded by the keyboard and without a return of it or any of the parts for operating it to a zero or initial position; to produce a keyboard controlled mechanism to receive location impulses and 50 from them control direction of movement and then produce a locking of the moving parts after their movement has been completed. Other objects of this invention will 55 be hereinafter pointed out or will otherwise appear in connection with the fol-

lowing description of an embodiment of the invention as shown in the accompanying drawings in which—

Figure 1 is a plan view of a well known type casting and composing machine embodying the present invention. 60

Fig. 2 is a plan view enlarged of the interpreting or selector device shown in Fig. 1.

Fig. 3 is a vertical section of said device 65 substantially on the line 3—3 of Fig. 4.

Fig. 4 is a horizontal section substantially on the line 4—4 of Fig. 3.

Fig. 5 is a cross section on substantially the line 5—5 of Fig. 2. 70

Fig. 6 is an elevation looking at the left end as shown in Fig. 3.

Fig. 7 is a sectional detail showing the worm and nut connection.

Fig. 8 is a perspective view of a plunger 75 or air pin, and

Fig. 9 is a schematic view illustrative of the pneumatic and mechanical layout by which the operation of the device may be readily understood. 80

The machine the general features of which are illustrated in Fig. 1 is of a well known class for producing individual types and requires herein no extended description; its general organization may be as 85 shown in Patent 625,998 granted May 30, 1899 to Lanston Monotype Machine Co. For identification purposes it may be of advantage to indicate by reference characters some of the more important parts of the 90 mechanism shown; for example, the paper controller tower A, the pin blocks B and B', the matrix positioning mechanism C and C', the mold D the molten metal pot E, the pump mechanism F, the cross slide G to 95 which the matrix case (not shown) is adapted to be hooked, the line hook H, the type channel I, the hand wheel J and its shaft K, the mold blade operating mechanism L and the normal wedge M cooperating with 100 the mechanism L to determine the setwise adjustment of the mold.

The relation and operation of these parts and of the other parts of the machine are well understood. The paper controller perforations govern the selection of pins in the pin blocks B, B', and the selected pins form stops for the matrix case positioning mechanism C, C' the mechanism C' of which also positions the normal wedge M whereby a 110

desired matrix in the case is properly positioned over the casting cavity of the mold D and the wedge is positioned correspondingly. The mold blade operating mechanism L, is also actuated to coöperate with the wedge M to position the mold blade to the set size adjustment corresponding with the matrix selected, the matrix is pressed against the mold and the pump mechanism 10 is operated to cast the type. Upon the cooling of the type, the matrix is lifted from the mold and the type is ejected by a forward movement of the mold blade to close the mold cavity, the cross-block or equivalent 15 part of the mold being meanwhile moved to a position not to interfere with the ejection of the type by the mold blade. Upon being pushed from the mold in this manner the type is carried by suitable conveying mechanism 20 into the type channel I and when a line has been thus ejected the line hook H and other mechanism not shown operate to move the line into the galley of the machine. Further description of the construction 25 and operation of this machine is deemed unnecessary because of its being entirely familiar to those skilled in the art.

The selector mechanism of the present invention, particularly shown at the top of 30 Fig. 1 and also in Figs. 2, 3, 4, 5 and 6, is controlled from the paper tower by suitable signal perforations in the controller strip communicating with the said mechanism through the air pipes 10 (Figs. 1 and 9) and 35 is designed to interpret the signal impulses received by it and thus selectively govern a definite function of the machine. As illustrated it governs the pointwise adjustment of a mold by selecting the desired 40 number of blades of a multiple blade mold and thus the keyboard operator is able to control the point size of the type to be produced by the machine.

The mold shown (Figs. 1 and 9) is of 45 similar structure to the multiple blade overhang type mold shown in the patent of John Sellers Bancroft and Amos L. Knight, Number 1328256, dated January 20, 1920. It embodies essentially the base plate 11 50 secured to the base of the machine, the cross block 12, the fixed blocks 13 and 14, the mold blades 15 and the adjustable slide 16. The mold blades are provided each with an aperture all of the apertures being in register or 55 alinement when all of the mold blades are in position to close the mold cavity. The slide 16 is provided with a locking extension 17 and with a pivoted lever 18 the ends of both extension and lever being adapted to 60 move through said alined apertures of the mold blades and thus be so adjusted that the extension maintains a definite number of mold blades locked in closed position while the lever acts normally to move the remaining 65 blades in open position, such action of

the part of the lever being due to the tension spring 19 secured at one end to the outer end of the lever and at the other end to the bracket 20 secured to the slide member 16. It will be seen that the lever 18 tends to 70 maintain the mold open with a cavity the point size of which depends upon the number of blades controlled by the lever. In the position of adjustment shown the lever controls three blades and the extension 17 75 serves to lock the remaining three blades. Movement of the slide 16 at right angles to the blades and at a time when all of the blades are closed will cause a selection of 80 the desired number of blades for control by the lever 18 and thus determine the point size capacity of the mold. When the slide is adjusted by hand a lock is desirable to hold it in adjusted position; but as shown herein the movement is caused by a nut and 85 worm device operated by the selector mechanism and the slide therefore requires no special lock. Further description of the mold is believed to be unnecessary in view of the disclosure in the patent above mentioned, to which reference may be made if it is desired to become acquainted with the 90 details of the mold construction. As to its bearing upon the present invention the mold may be of any kind capable of producing a 95 variety of type sizes, particularly in a pointwise direction, and being provided with adjustable means for producing the appropriate setting for the desired type size: likewise the selector or interpreting mechanism 100 per se may be utilized to move or control the movement of other parts in response to signals in the record especially where a number of positions of adjustment are desired for the least possible number of signals 105 and the movement is directly from one position to another.

The selector or interpreting mechanism is, in the embodiment shown, suitably located at one side of the casting machine 110 with its selector element, which as shown is in the form of a plate, movable at right angles to the direction of movement of the mold blades 15. As shown it is supported by the bracket 21 carried by the main frame 115 of the machine. Upon the bracket 21 is a pin block 22 above which and spaced therefrom by the side supports of the casting 23 are cylinders 24 and 25 forming a part of 120 said casting. Slidably supported upon the pin block and below the cylinders is the selector slide 26. Piston 27 in cylinder 24 is connected with piston 28 in cylinder 25 by a connecting rod 29 which has secured 125 centrally thereof a depending support 30 the lower end of which is attached to the selector slide 26. When air under pressure 130 is admitted into pipe 31 at the end of cylinder 24 and pipe 32 at the end of cylinder 25 is open to exhaust, the air pressure thus

admitted to cylinder 24 moves the two pistons and their connection with the selector slide so that the latter is moved to the right in Figs. 2, 3 and 4. On the other hand when 5 pipe 31 is exhausted and air under pressure is admitted through pipe 32 an opposite travel of the selector slide takes place. The pin block 22 is provided with cylindrical cavities for the air pins or plungers in 10 plural groups in the form of a row of air pins 33^a and alongside of and parallel to it another row 33^b. A pin of one row forms with the opposite pin of the other row a pair of pins both of which receive air simultaneously through its air pin inlet pipe 10. Each inlet pipe 10 is branched below the 15 bracket 21 and each branch leads below one of the air pins of a pair. There are provided as many pairs of air pins as there are mold blades or other instrumentalities, sizes or 20 positions to be thereby selectively controlled. The air pins are individually pressed downward against the bottom plate 35 by a spring 36. The top of each spring presses 25 against a wall formed by reducing the size of the air pin cavities in the pin block 22, such wall being near the upper surface of the pin block. The air pins, which may constitute stop or similar selector members, 30 are constructed as shown particularly in Fig. 8 and are provided with a lower portion 33^c of a diameter to fit the large diameter portion of the cylindrical cavity for the pin, an intermediate portion 33^d of lesser 35 diameter around which the spring 36 is coiled so that its bottom presses against the top wall of the lower portion 33^c of the pin and a top portion 33^e of small diameter which when the pin is actuated rises through 40 the pin block into one of two longitudinal staggered slots 37^a and 37^b in the selector slide or plate, the slot 37^a being located to move over the row of pins 33^a and the slot 37^b parallel with the first mentioned slot and 45 located to move directly above the row of pins 33^b. These slots extend to the right and left of a central or neutral point on the selector slide except that they overlap sufficiently so that each pin of a pair actuated 50 at such point will rise into and through its corresponding slot. When air is admitted to any other pair of pins than those so located, one only of such pair of pins may protrude through its slot; the other of such 55 pair is prevented from rising by contact with the bottom of the selector plate.

It will be observed that since in every position except the neutral position, only one pin of a pair which has received a pneumatic impulse resulting from keyboard action may project through the plate, the latter's position determines which pin of a pair may rise and thus the plate has a selective function as will later more clearly appear. From a single pipe 10 therefore

air under pressure will raise a pin 33^a or 33^b of a pair according to whether or not the slot 37^a is located above the first pin or the slot 37^b is above the second pin; in other words, the position of the slots (which means of course the position of the plate) 70 relatively to the pairs of air pins determines which of the pins of a pair is raised. The raising of any pin 33^a of one row through the slot 37^a of the selector plate 26 causes its upper end to engage with a bell crank lever 38^a pivoted to the casting 23 at 75 39^a. The bell crank is thus tilted by the movement of the pin and operates a control or governing device in the form of a throttle valve 40^a in a casing 41^a forming part of the casting containing the cylinder 25. The valve casing 41^a has an air pressure inlet pipe 42^a through which air is admitted to the valve chamber 43^a. When the valve 40^a is pressed by the bell crank 38^a air is admitted from the chamber 43^a to the pipe 32, previously mentioned. Upon the release of the air pin 33^a the valve 40^a is returned to 80 its normal position by the pressure in the chamber 43^a and in so returning, tilts the bell crank back to its original position. In such position the pipe 32 is exhausted to the atmosphere through the exhaust port 44^a. The construction of this valve, which is very 85 clearly shown particularly in Fig. 5 of the drawing, is well known and needs no further description here.

Likewise, when a pin 33^b is raised through its slot 37^b it encounters a bell crank lever 38^b similar to the bell crank lever 38^a but pivoted at 39^b on the opposite side of the selector plate support 30. When tilted by the air pin the upper arm of the bell crank 38^b strikes against valve 40^b in a casing 41^b 100 forming a part of the casting of cylinder 24 and air is admitted from inlet pipe 42^b into valve chamber 43^b and into pipe 31, previously mentioned. The valve 40^b and its casing and arrangement are of the same 105 general structure as those of valve 40^a. The pipes 42^a and 42^b are connected with a single pipe 42 (Figs. 1 and 9) leading to the selector plate timing device connected with the shaft K as will be described hereinafter.

The pipes 10 leading to the air pins are connected, as has been before stated, with the paper tower so that they operate when a perforation or signal in the paper is advanced to the proper position in the tower. 110 The adjusting movement of the selector plate 26 however is desired at a time when the mold blades 15 are in closed position and their apertures are therefore in alignment. The signal impulse precedes the required adjustment time and a pin raised through its slot by such impulse may drop, due to the cutting off of air pressure, before the plate and the mold adjustment slide has been permitted to move. Because of this 115 120 125 130

peculiarity of timing in the machine illustrated, it is desirable to provide a catch device to maintain an actuated pin in its raised position. A suitable catch device is illustrated in the drawings and will now be described, it being understood that the catch device is necessary only because of the timing of the particular machine to which the invention is applied. Each air pin is provided with a notch 33^c, (see Fig. 8) and such notch is designed to be engaged by a catch or detent, there being a row of such catches 45^a corresponding with the pins 33^a and another row 45^b corresponding with the pins 33^b. The detents 45^a are pivoted centrally to the pin block at 46^a and are each provided with a finger 47^a extending below the slide 26 for engagement with the notch 33^c in the corresponding air pin. A spring 48^a connects the rear end of each detent 45^a with a stud 49^a in the pin block 22, so that the finger 47^a is caused to be pressed normally against the side of the air pin 33^a. When the pin is raised by air pressure in the pipe 10 to its maximum upper position the finger 47^a engages in the notch 33^c and holds the pin in its upper position until released. The detents 45^b pivoted at 46^b are provided each with a finger 47^b and a spring 48^b connected with a stud 49^b, the arrangement of detents 45^b being exactly like that of detents 45^a except that the former are oppositely placed and are adapted to engage with notches in the pins 33^b. Slidable in longitudinal channels in the pin block are catch release slides 50^a for the detents 45^a and 50^b for the detents 45^b. These slides are provided with upraised projections 51^a and 51^b respectively, such projections being adapted to engage with the rear portions of the detents so that upon movement of the release slides against the tension of the springs 48^a, 48^b the detent fingers 47^a, 47^b are pulled out of the notches 33^c in the air pins 33^a and 33^b and the latter are forced to their normal positions by the action of coiled springs 36. The detent release slide 50^a is pivotally connected at its end with a lever arm 52^a and the slide 50^b is similarly connected with an arm 52^b. The arms 52^a and 52^b extend downwardly from a hub member 53 pivoted to the casting 23. This member is also provided with a downwardly extending central arm 54 longer than the arms 52^a and 52^b and the central arm is attached by the connecting rod 55 to the piston 56, the cylinder of which is bored in the end of the pin block 22. Air is admitted to said cylinder through the air inlet pipe 57. This pipe leads from a detent release timing device associated with shaft K which will presently be described.

When a pin 33 is raised through a selector plate slot a finger of the detent associated with the pin will engage with the pin

notch 33^c and hold the pin in place even though air may be thereafter exhausted from the pipe 10 leading to said pin. At a designated time for restoring the pin to its normal position, air is admitted through the pipe 57 which causes the piston 56 to move the arm 54 and the catch release slide arms 52^a and 52^b, and consequently the catch release slides 50^a and 50^b. The projections 51^a are all moved back to the left, Fig. 4, and one of such projections engages with the rear end of any detent which has its finger 47^a in the slot of the raised pin. The projection 51^a thus moves the rear end of the detent against the tension of its spring and removes the finger from the slot so that the air pin may be restored to its normal position. A spring 58 secured to the cylinder 24 and the arm 54 returns the slides 50 to normal position when air is exhausted from pipe 57.

The selector plate 26 is provided with a rack 59 in mesh with a pinion 60 on the end of a shaft 61, the latter shaft, as will be seen in Fig. 1, extending parallel with the mold blades and the mold blade operating devices and being supported in bearings 62 supported on a fixed bracket near the rack 59 and bearings 63, 64 on the frame of the casting machine in proximity to the mold. Between the bearings 63 and 64 there is provided a worm 65 engaging with the nut 66, the worm and nut being shown more particularly in Fig. 7. A pin 67 shown in said figure extends through an aperture in the nut and is seated in the two bearings 63, 64 thus preventing the nut from turning. Rotation of the shaft 61 will therefore produce a movement of the nut longitudinally of said shaft. A bell crank lever 68 centrally pivoted to the frame of the machine at 69 has one end connected with the nut 66 by a pin and yoke connection, the other end of the lever being connected with the slide 16 of the mold by a similar connection. It will be apparent that a movement of the selector plate causes a movement of the shaft and of the bell crank lever 68 to slide the mold slide 16 in one direction or the other depending upon the direction of movement of the selector plate.

The selector plate timing device previously referred to may be simply an air valve operated to connect the pipe 42 with air under pressure for controlling the operation of the selector plate; similarly the detent release timing device may comprise another valve for controlling the admission of air under pressure to the catch release pipe 57. The devices may conveniently be attached in proximity to hand wheel shaft K which latter rotates at a definite relation to the various movements of the machine. On this shaft K, as shown, are the cams 70 and 71 operating respectively the bell crank levers 130

72 and 73 (see Figs. 1 and 9); the former lever when engaged by the raised portion of the cam 70 operates a suitable valve such as the well known button valve 74 (Fig. 9) 5 to cause air pressure to pass from the constant air pipe 75 into pipe 42 leading to the selector plate cylinder throttle valves 40^a, 40^b; the latter lever 73 is operated similarly by the cam 71 to admit air through valve 76 10 from pipe 75 to pipe 57 and thus cause a release of the air pin detents. Both levers when they have ridden off the high places of their cams return their valves to exhaust the pipes 42 and 57 respectively, the return of 15 the levers and valves being assisted by springs as 72^a.

The air pins 33 are blown up directly from the paper tower and when so raised operate to open one or both of the throttle 20 valves 40^a and 40^b. Air under pressure cannot traverse these valves to the power cylinders 24, 25 until the pipe 42 is connected with air under pressure in pipe 75. Moreover in the machine illustrated it is not de- 25 sired to admit power to these cylinders to cause movement of selector plate 26 and, resulting therefrom, of mold slide 16 except when the apertures in the various mold blades are in alinement; in other words, 30 when the mold blades are in closed position. Accordingly the cam 70 is arranged on shaft K in such manner as to effect communication between pipes 75 and 42 when the mold blades are in closed position. Because of the 35 fact that in the particular type of composing and casting machine illustrated this condition of mold closure occurs very much later in point of time than the admission of air to the air pins by the paper controller it is 40 necessary in this case to provide air pin catches such as have been described. These catches take hold, as has been stated, immediately upon the sufficient raising of the air pins. Their release is governed by the cam 45 51 which is arranged to act upon bell crank 73 to open valve 76 so as to establish communication between constant air pipe 75 and pipe 57 at a time after the selector plate has been moved to selected position and before 50 the advent of another signal impulse to raise an air pin for the next selection.

The arrangement provides a retarded action which permits the record signals to set parts to effect selection of positions of other 55 parts but the actual selection and final movements are effected at a different time in the rotation cycle of the machine with the result that the timing may be made correct without imposing destructive strains or 60 speed to the moving parts.

In the operation of the casting machine the paper controller is fed forward in the paper tower A step by step; its perforations may control matrix selection or other 65 functions of the machine; and for the illus-

trated embodiment of the present invention the controller is assumed to have a perforation signal to communicate properly with a pipe 10 leading to a pair of pins 33^a, 33^b below the selector plate 26. Air 70 under pressure immediately tends to force these pins upwardly and results in the raising of at least one of them, which on rising extends into or through one of the slots 37^a, 37^b in the selector plate and tilts one of the 75 levers 38^a, 38^b to open one of the valves 40^a, 40^b. Also, upon reaching its raised position a catch 45^a or 45^b will hold the pin in such position in the way already described. The position of the plate at any 80 time determines whether both pins 33 of a pair shall rise to lock the plate against movement, or only one of such pair and in the latter case which one of the pair to control movement of the plate to a new position. The selected pin determines which valve of the pair 40^a, 40^b is opened and consequently in what direction the plates shall be moved. The movement of the plate is therefore direct from one position to the 85 next without any return to a zero or initial position by it or by any of the parts by which it is operated. The cam 71 on shaft 90 K, turning in the direction indicated by the arrow in Fig. 9, thereafter, that is, at a time when the mold is closed, operates 95 to open the valve 74 whereupon air under pressure passes from pipe 75 to pipe 42 and thence through the open valve of the pair 100 of valves 40^a, 40^b to the corresponding one 105 of the pair of power cylinders 24 or 25. Assuming then an air pin 33^a is raised through the slot 37^a and causes the opening 110 of valve 40^a and is caught and held by a catch 45^a; upon the opening of the timing valve 74 air from pipe 42 will traverse valve chamber 43^a and pass by the open valve 40^a into pipe 32 leading to cylinder 25. In the meantime cylinder 24 is open to exhaust through pipe 31 and exhaust port 44^b of closed valve 40^b. The pistons in cylinders 115 24 and 25 are therefore moved by the pressure in the latter cylinder and this movement causes a movement of the selector slide 26 to the right as seen in Fig. 9 until it is arrested by the abutment 37^c, formed as shown by the end of its slot 37^a striking against the raised air pin. Such movement causes a rotation of the shaft 61 and consequently movement of mold slide 16 to select the number of blades corresponding with the particular air pin which has been raised by signal. It is clear, of course, that the blowing up of a pin 33^b would similarly 120 result in an opposite movement of the selector slide 26 until its abutment 37^d engages the operated pin, and of the mold slide 16. When the selector slide is in middle position, as shown, the mold slide, it 125 130

will be noted, is also in middle position, having selected three of the six blades. It may also be pointed out that in whatever position the selector slide is left a controller signal calling for no change of selection of mold blades—such signal may be termed a repeat signal—will blow up both air pins of a pair, the slots 37^a and 37^b being overlapped sufficiently (see Fig. 4) to 10 allow this. In such case both valves 40^a, 40^b are opened and air will subsequently be admitted to both cylinders 24, 25. The result will be an equalization of pressure and consequently no movement of the selector plate. It is to be noted also that when both pins of a pair are raised the plate is locked against movement, the inner end of each slot 37^a, 37^b being stopped against an air pin. This locking feature is operative in any case in which air pressure 20 against the air pins is sufficiently prolonged or in which the paper controller signal and the adjustment are adapted to take place substantially at the same time because if 25 at first one pin of a pair only rises, it accomplishes a movement of the selector plate to position the inner wall of its slot against the said pin and the second pin which has meanwhile pressed against the bottom of 30 the plate will also rise into its slot when the above positioning has been accomplished. When both pins are raised the plate will be locked against movement in either direction.

35 Obviously the inner end walls 37^c, 37^d of the slots in the plate simply form shoulders or abutments for contact with the pins and hence the formation of slots is not essential but is a convenient and cheap construction.

40 I claim:

1. In a typographic machine the combination of a pointwise adjustable mold and means responsive to keyboard control for adjusting said mold pointwise.
2. In a typographic machine, the combination of a mold adjustable both pointwise and setwise, means responsive to keyboard control for adjusting said mold setwise and 50 means responsive to keyboard control for adjusting said mold pointwise.
3. In a typographic machine the combination of a mold provided with a plurality of blades and with adjustable mechanism for determining which of said blades shall be operated, and means responsive to keyboard control for adjusting said mechanism.
4. A typographic machine embodying the following instrumentalities to wit: a mold 60 provided with a plurality of blades and with adjustable mechanism for determining which of said blades shall be operated, a selector device for adjusting said mechanism embodying a plurality of selector members 65 corresponding with the various positions of

adjustment of said adjustable mechanism, means for selectively operating said members, a selector plate movable against an operated member, means for connecting said plate with said adjustable mechanism, and 70 means operated by said operated member to control the movement of said plate.

5. A typographic machine embodying the following instrumentalities, to wit: an adjustable mechanism, a selector device for 75 adjusting said mechanism and embodying a plurality of selector members corresponding with the various positions of adjustment of said adjustable mechanism, means for selectively operating said members, a selector plate movable against an operated member, means for connecting said plate with said adjustable mechanism and means 80 operated by the operated selector member for controlling the movement of said plate. 85

6. A typographic machine embodying the following instrumentalities, to wit: a selector member, a selector plate movable to a position determined by said member, and means operated by said member for controlling the movement of said plate. 90

7. A typographic machine embodying the following instrumentalities, to wit: a plurality of members selectively operated by keyboard control, a selector plate movable 95 against an operated member, and means operated by said member for controlling the movement of said plate.

8. In a typographic machine, a selector device comprising a pair of selector members, a plate provided with means for selecting by its position relative to said members which one of the pair thereof shall be operated and means for moving said plate, said last mentioned means being controlled by 105 the operated selector member.

9. A signal controlled typographic machine embodying a movable selector plate, plural groups of selectors for determining the selected position of the plate characterized by corresponding individual selectors of the groups forming pairs responsive to the same signal, motor mechanism for moving the plate in opposite directions, means responsive to any operated selector of one 110 group for effecting the movement in one direction, means responsive to any operated selector of the other group for effecting the movement in the other direction, and means movable simultaneously with the plate for 115 preventing the operation of the selectors of one group or the other in accordance with the desired direction of movement.

10. A signal controlled typographic machine embodying means for selectively positioning a movable part, such means comprising plural groups of selectors, means whereby corresponding selectors in each group are made responsive to the same signal, a selector plate having abutments for coöpera- 125 130

- tion with the selectors of each group to position the plate, selector movement preventing parts movable simultaneously with the plate for determining in which group a selector 5 shall operate in response to signal, motor mechanism for moving the plate in opposite directions, and means controlled by the operated selector for determining the direction of such movement.
- 10 11. A typographic machine embodying the following instrumentalities, to wit: a selector device comprising a pair of selector members, a movable plate provided with means for selecting by its position relative 15 to said members which one of the pair thereof shall be operated, means for operating said member, and means operated by said operated member to control the movement of said plate.
- 20 12. In a typographic machine, a selector device comprising a plurality of pairs of selector members, said pairs being responsive to keyboard control, a plate provided with means for selecting by its position 25 relative to said pairs of members which one of a pair thereof shall be operated and means for moving said plate in opposite directions, said means being controlled by the selected member.
- 30 13. A typographic machine embodying the following instrumentalities to wit: a selector device comprising a plurality of pairs of air pins, keyboard controlled pneumatic means for selectively operating said pairs 35 of pins, a plate provided with means for selecting by its position relative to said pairs of pins which one of a pair thereof shall be operated, pneumatic means for moving the plate in one direction, a valve de- 40 vice controlled by one operated pin of a pair for admitting fluid under pressure to said pneumatic means, separate pneumatic means for moving the plate in the opposite direction and a valve device controlled by 45 the other operated pin of a pair for admitting fluid under pressure to said second-mentioned pneumatic means, whereby the direction of movement of the plate depends upon which one of a pair of pins is op- 50 erated.
14. A typographic machine embodying the following instrumentalities to wit: a selector device comprising a plurality of pairs of selector members, said pairs being op- 55 erated by keyboard control, a selector plate located above said members and movable against an operated member as a stop, said plate being provided with a pair of abutments whereby in any position of the plate 60 one member of a keyboard selected pair of members is movable into the path of one of said abutments and the plate thus selects which member of a selected pair of members shall be operated, means operatively 65 controlled by one operated member of said
- pair of members for moving the plate in one direction and separate means operatively controlled by the other operated member of said pair of members for moving the plate in the opposite direction, whereby the position to which the plate is to be moved is dependent upon the keyboard selection of a pair of selector members and the direction in which the plate is to be moved is dependent upon which member of a selected 70 pair of members is permitted by the plate to operate.
15. In a typographic machine, a selector device comprising a pair of selector members, a selector plate located above said members and provided with a pair of abutments whereby in any position of the plate one member of said pair of members is movable into the path of one of said abutments and means for moving said plate, said means being controlled by the said movable member.
16. A typographic machine embodying the following instrumentalities to wit: a pair of selector members, a selector plate located above said members and provided with a pair of staggered slots overlapping at their proximate ends whereby in any position of the plate one member of said pair of members is movable into one of said 95 slots and in the neutral position of the plate with respect to said members both of said members are movable into the overlapping ends of said slots and thereby lock the plate against movement, means for moving the plate in opposite directions to said neutral position, said means being controlled by the movable member of said pair of members.
17. In a typographic machine, a selector device comprising a pair of selector members, a selector plate located above said members and provided with a pair of staggered slots, whereby in any position of the plate one member of said pair of members is movable into one of said slots, means for moving said plate in opposite directions, said means being controlled by the movable member.
18. In a typographic machine, a selector device comprising a pair of selector members, a plate provided with means for selecting by its position relative to said members which one of the pair thereof shall be operated, means operatively controlled by one of said members for moving the plate in one direction and separate means operatively controlled by the other of said members for moving the plate in the opposite direction whereby the direction in which the plate is to be moved is dependent upon the position thereof.
19. A typographic machine embodying the following instrumentalities, to wit: a pair of selector members, a selector plate

movable against an operated member acting as a stop, means for selectively operating one member of said pair of members, means operatively controlled by one member of 5 said pair of members for moving the plate in one direction, and separate means operatively controlled by the other member of said pair of members for moving the plate in the opposite direction, whereby the direction of movement of the plate depends upon 10 which member of the pair of members is operated.

20. A typographic machine embodying the following instrumentalities, to wit: a 15 pair of selector members, means for operating both members, a selector plate slidably mounted above said members and having a pair of abutments into the path of each of which one of said members is movable, said abutments being arranged so that 20 in a definite position of the plate one of said members is movable into the path of its abutment and the other of said members is prevented from moving by the plate, 25 means for sliding the plate in opposite directions and means controlled by the movable member to govern the direction of movement of the plate.

21. A typographic machine embodying 30 the following instrumentalities, to wit: a plurality of pairs of selector members, keyboard controlled means for selectively operating one of said pairs, a selector plate slid-

ably mounted above said members and having a pair of slots into each of which one 35 member of each pair of members is movable, said slots being staggered so that in a definite position of the plate one of the members of each pair of members is movable into the corresponding slot and the other member of each pair is prevented from moving by the plate, whereby the said position of the plate determines which member of a selected pair shall be moved, means for sliding the plate in opposite directions and 40 means controlled by the moved member to govern the direction of movement of plate. 45

22. A typographic machine embodying the following instrumentalities to wit: a selector member, means for operating said member, a detent for maintaining it in operated position, a selector plate, means for moving said plate against said member, means set in operative position by said member for controlling the operation of said 50 moving means, a timing device controlled from a movable part of said machine for governing the time of operation of said moving means through said controlling means therefor and a timing device controlled 55 from a movable part of said machine for releasing the said detent and allowing the return of the member to normal position when the plate has been moved against said member.

MAURITZ C. INDAHL.
